US00D754098S

(12) **United States Design Patent**
Teramoto et al.

(10) **Patent No.:** US D754,098 S
(45) **Date of Patent:** ** Apr. 19, 2016

(54) **SPEAKER**

- (71) Applicant: **DIASOUL Corporation**, Osaka (JP)
(72) Inventors: **Kohei Teramoto**, Osaka (JP); **Takanori Hikima**, Tokyo (JP)
(73) Assignee: **DIASOUL Corporation**, Osaka (JP)
(**) Term: **14 Years**
(21) Appl. No.: **29/521,486**
(22) Filed: **Mar. 24, 2015**

(30) **Foreign Application Priority Data**

- Sep. 25, 2014 (JP) 2014-021267
(51) **LOC (10) Cl.** **14-03**
(52) **U.S. Cl.** USPC **D14/213**; D14/215
(58) **Field of Classification Search**
